UNITED STATES PATENT OFFICE.

VALENTINE SCHUCK, OF NEW YORK, N. Y., ASSIGNOR TO THE SUTRO BROTHERS BRAID COMPANY, OF SAME PLACE.

DESIGN FOR BRAID.

SPECIFICATION forming part of Design No. 26,814, dated March 23, 1897.

Application filed February 6, 1897. Serial No. 622,361. Term of patent 14 years.

To all whom it may concern:

Be it known that I, VALENTINE SCHUCK, a citizen of the United States, residing at New York, in the county and State of New York, have invented and produced a new and original Design for Braid, of which the following is a specification.

The design consists of a braid comprising a strand or thread running diagonally from an edge of the braid to and beyond the opposite braid edge and formed or bent into a loop outside such second edge, such strand, after being thus looped, running back diagonally or bias to and about the first-named edge of the braid.

The design is illustrated in the annexed drawings, in which—

Figure 1 is a face view of the braid. Fig. 2 is a sectional view of Fig. 1 sectioned along $x x$, Fig. 1. Fig. 3 is a section along $y y$, Fig. 1.

The braid or body of the device is shown with its edges at 1 and 2. A strand or thread starting, for example, from point 3 runs bias or diagonally from edge 1 to the point 4 at edge 2 and thence beyond or outside of such edge 2, where said strand is bent or thrown

into a loop 5. From said loop 5 the strand returns bias or diagonally to the edge 1, as at the point 3', thence passing on again, as before. The strand-section running from edge 1 to a loop by being placed on the opposite side or face of the braid-body from that occupied by the strand section or length which runs from said loop to edge 1 will give a pleasing effect. By having the adjacent strands each run into a loop a close or compact arrangement of loops is obtained, and said strands, being twisted, give a firm or twisted or eye-shaped appearance to each loop.

The design gives a striking and characteristic appearance.

What I claim as new, and desire to secure by Letters Patent, is—

The design for a braid as herein shown and described.

In testimony whereof I have hereunto set my hand in the presence of two subscribing witnesses.

VALENTINE SCHUCK.
